TELECOMMUNICATION SYSTEM

Percy Edward Alexander Cowley, Coventry, and
Eric Clifford Walls, Liverpool, England, assignors to Automatic Telephone & Electric Company Limited, Liverpool, England, a British company

Application December 3, 1943, Serial No. 512,816
In Great Britain January 20, 1943

4 Claims. (Cl. 178—44)

1

The present invention relates to telecommunication systems particularly those employing carrier current, and finds advantageous application to systems in which, for gain control purposes, a pilot frequency is transmitted over the same medium as the carrier speech and/or signalling frequencies and has a frequency value of the same order thereof. The chief object of the invention is to minimise the adverse effect of ambient temperature variation on the characteristics of the filters employed which in the particular application referred to may upset the control function of the pilot frequency.

In such systems the pilot frequency in following the same course or path as the carrier frequencies is subjected to the same transmission loss. Thus any common apparatus such as line or directional filters in said path may have a transmission loss which varies with ambient temperature without affecting the relative received levels of the pilot and carrier frequencies. At the receiving end, where filters are employed to separate the pilot from the carrier frequencies, it is essential for satisfactory operation that the filters individual to said carrier and pilot frequencies shall have equal loss/temperature coefficients, that is to say, that the respective losses with increase in temperature shall either remain constant or shall increase to an equal extent.

It is found that the band pass carrier receiving filters have substantially zero loss/temperature co-efficients, but the pilot receiving filter has, due to its highly selective nature a considerable positive loss/temperature co-efficient. The invention provides a simple method of compensation whereby a substantially zero loss/temperature co-efficient can be obtained for the pilot frequency receiving equipment.

According to one feature of the invention, in a telecommunication system employing filter circuits the attenuating effect of which varies with temperature, a compensating arrangement is provided in which an amplifier employed in conjunction with a filter circuit is arranged to have a positive gain/temperature coefficient of such value as to compensate substantially completely for the positive loss/temperature coefficient of the filter.

According to another feature of the invention, in a telecommunication system employing a pilot frequency transmitted over the main communication channel for the purpose of gain control, a compensating arrangement is provided in which the effect of the greater loss/temperature

2

coefficient of the filter for the pilot frequency compared with that of the filter for the main channel is counteracted by including in the pilot frequency receiving circuit an amplifier arranged to have a positive gain/temperature coefficient.

The invention will be better understood from the following description of one method of carrying it into effect which should be taken in conjunction with the accompanying drawing 10 comprising Figs. 1 and 2. Fig. 1 shows in block schematic form speech side-band and pilot frequency transmitting and receiving arrangements in a typical multi-channel carrier telecommunication system using single side-band speech transmission and employing different channels for transmission in each direction over an ordinary telephone line also used for audio frequency transmission. Fig. 2 shows circuits of a one-valve temperature-compensated pilot frequency 15 amplifier of the negative feedback type, the feedback circuit incorporating resistance elements having different temperature co-efficients.

Referring now to Fig. 1, 11 represents an audio-frequency telephone line on which a multi-channel carrier system is superimposed. At the sending and receiving ends SE and RE, there are inserted the audio frequency low-pass filters ALP1 and ALP2 which serve to exclude the carrier and pilot frequencies from the sending and 20 receiving audio frequency telephone apparatus. At the sending end SE, carrier frequency speech is fed to one of a number of leads such as 10 from the modulating equipments, not shown, while the pilot frequency is generated by the oscillator PO. The equipment common to the 25 pilot and speech side-band frequencies is designated SP1 and includes the directional carrier filter together with amplifying equipment. The equipment individual to the speech side-bands is designated S1 and includes the band-pass single side-band sending filters.

At the receiving end RE, SP2 designates the equipment common to the pilot frequencies and speech side-bands and includes the directional carrier filter together with a control amplifier which is normally set to provide a zero overall gain, but the gain of which is adjustable in accordance with the received pilot frequency level. The equipment individual to the speech side-bands is designated S2 and includes band-pass receiving filters via which the received side-bands are directed over a lead such as 12 to their appropriate receiving demodulators. The highly selective pilot receiving filter is designated PRF, the succeeding pilot frequency amplifier is desig-

nated PA, while PLI represents pilot frequency level indicating equipment by means of which the gain of the common control amplifier in equipment SP2 can be manually or automatically adjusted in accordance with the received pilot frequency level. The positive loss/temperature coefficient of the pilot receiving filter PRF is considerable owing particularly to the nature of this filter, while that of the band-pass speech side-band receiving filters S2 is substantially zero. In order to match the loss/temperature characteristics of the pilot frequency receiving equipment with that of the speech side-band receiving equipment, it is arranged that the pilot frequency amplifier PA is given a positive gain/temperature co-efficient which will compensate for the positive loss/temperature co-efficient of the preceding pilot receiving filter PRF.

One suitable form of temperature-compensated amplifier is shown in Fig. 2 where leads 13 and 14 extend from the pilot receiving filter and the output leads 15 and 16 extend to the pilot level indicator. The grid of valve V automatically receives a standing negative bias by virtue of the biasing resistance R1 and its associated bypass condenser C1, while one of the two secondary windings of the output transformer T2 is centred-tapped and is connected up with two resistance elements R and S so as to form a bridge network, across the centre points of which a feedback circuit is taken via the secondary winding of input transformer T1 to the valve grid. Resistance element R is made up of one of the known forms of copper/nickel alloy which has a zero temperature co-efficient, while resistance element S utilises iron wire which has a considerable positive temperature co-efficient.

At some temperature which is preferably well above that to which the apparatus will be subjected, the bridge is arranged to be balanced and resistances R and S are conveniently arranged to have values of the order of 20,000 ohms each. There is then zero feedback from anode to grid via the feedback path. At the highest expected ambient temperature, the static resistance R may maintain its 20,000 ohm value, while resistance S falls to a value of the order of 15,000 ohms with the result that the feedback is made negative. With further decrease in temperature the resistance S lowers correspondingly, thus increasing the negative feedback and so decreasing the gain of valve V. By the choice of suitable values for resistances R and S the gain/temperature characteristic of the amplifier can be adjusted to give the required performance.

It may be that certain band-pass receiving filters have a small positive loss/temperature characteristic in which case the compensation in the pilot frequency amplifier will be made such

that there will be a corresponding slight overall positive loss/temperature co-efficient for the pilot receiving equipment.

It will be understood that the invention is not limited to the particular method shown of producing the required amplifier gain/temperature characteristic.

What we claim as new and desire to secure by Letters Patent is:

1. In a telecommunication system, a compensating arrangement comprising in combination a communication channel, a pilot frequency oscillator connected to one end of said channel, a filter circuit having a positive loss/temperature coefficient, said filter circuit being sharply tuned to the frequency of said pilot frequency oscillator and connected to the other end of said channel, an amplifier for amplifying said pilot frequency after its passage through said filter, temperature-responsive means in said amplifier, means controlled by said temperature-responsive means for automatically altering the gain of said amplifier so as to compensate for the increased loss in said filter with increase of temperature, and an indicator connected to the output of said amplifier for indicating the level of said pilot frequency.
2. In a telecommunication system, a compensating arrangement comprising in combination a communication channel, a pilot frequency oscillator connected to one end of said channel, a filter circuit having a positive loss/temperature coefficient, said filter circuit being sharply tuned to the frequency of said pilot frequency oscillator and connected to the other end of said channel, an amplifier including a thermionic valve with negative feedback for amplifying said pilot frequency after its passage through said filter, temperature-responsive means in said amplifier, and means controlled by said temperature responsive means for automatically altering the amount of feedback to said valve so that with increase of temperature the increase of gain of said amplifier compensates for the increased loss in said filter.
3. A compensating arrangement in accordance with claim 2 in which the sense and amount of the feedback is controlled by a bridge arrangement employing two resistances composed respectively of materials having appreciably different resistance/temperature coefficients.
4. A compensating arrangement in accordance with claim 2 in which the sense and amount of the feedback is controlled by a bridge arrangement employing two resistances, one resistance being composed of a copper-nickel alloy having a substantially zero temperature coefficient and the other resistance being composed of iron wire having a high positive temperature coefficient.
